UNITED STATES PATENT OFFICE

CHARLES A. MCPHERSON, OF EDGAR, MONTANA

TOY

Application filed May 24, 1932. Serial No. 613,279.

The object of this, my present invention, is the provision of a gyroscopic toy which, when the fly wheel is turned rapidly with a string will balance itself on a cord track which is stretched between two points, and whereby the toy will travel toward one of such points, and when such point is elevated, the toy will travel in an opposite direction toward the other point, so that by raising and lowering the ends of the track the toy will continue in a backward and forward movement for a long period of time, the toy being also provided with means to prevent the same from falling off of the track when the fly wheel thereof ceases to rotate.

To the attainment of the foregoing the invention consists in the improvement as hereinafter described and definitely claimed.

In the drawing:

20 Figure 1 is a side elevation of a gyroscopic toy in accordance with this invention.

Figure 2 is a top plan view thereof.

Figure 3 is a transverse sectional view approximately on the line 3—3 of Figure 2.

25 Figure 4 is an elevation of the guard.

My improved toy contemplates the employment of a carriage. The carriage in the showing of the drawing is made up of two metal strips which at points adjacent 30 to its center and adjacent to its ends are riveted or otherwise connected together. The body 1 of the carriage, at the center thereof, has the strips comprising the same bent outwardly and extended longitudinally 35 in a plane with the body 1, thus providing the frame with a substantially rectangular open portion 2. The plates constituting the frame, adjacent the ends thereof are also bent outwardly and are continued longitudinally in parallelism so that each end of the body is forked, as at 3. Journaled between the parallel arms at the forked ends of the body there are the short shafts or trunnions 40 for peripherally grooved wheels 4.

45 The longitudinal and parallel portions at the central part 2 of the body 1 are provided with alining openings to receive therein trunnions 5 on the ends of a shaft 6 which is fixed on and depending from the vertical ring 50 member 7 for the gyroscope. The lower end

of the ring has its inner face provided with a V-shaped depression to receive therein the conical end of the shaft 8 that extends through the hub of the fly wheel 9. The second end of the shaft 8 is also cone-shaped and received in the conical depression in the outer end of a short bolt member 10 which is screwed through the top of the ring 7. The ring 7 has centrally connected thereto or may be formed with a horizontal or rightangular- 60 ly arranged ring 11.

The frame, adjacent one of its ends, has fixed thereon the upper and reduced portion of a metal guard 12. The guard may be of wire or may be in the nature of a thin metal strip and from its connected portion the guard is provided with downwardly extending outwardly inclined arms 13, and the lower ends of these arms are rounded inwardly, as at 14, and the outer faces of the said rounded portions 14 are in contact with each other, but the extremities thereof are tapered or flared away from each other to afford a V-shaped mouth 15 between the rounded or jaw ends 14 of the guard. The purpose of this 70 will presently be apparent.

A pull cord 16 is guided around the upper portion of the shaft 8 and has one of its ends fixed to the said shaft, and a pull upon the cord 16 will cause the rotation of the shaft 8 80 and the fly wheel which is fixed thereto.

The peripherally grooved wheels 4 of the carriage are designed to travel upon a track 17. The track is in the nature of a flexible element, such as a cord and is of sufficient length so that the ends thereof may be held between the fingers of the outstretched arms of a person or the track may be of such length that the ends thereof are gripped between the fingers and thumbs of two persons. The track may be initially sustained in a horizontal position and the traveling toy may be started from one end of the track. When the toy reaches the second end of the track the operator slightly elevates such end, causing the toy to travel along the track toward its starting point and when the toy reaches such point the track is elevated so that the toy will travel on the track in an opposite direction, and thus by raising and lowering the 100

ends of the track when the traveling toy is in close proximity to the ends of the track the toy will travel on the track for a comparatively great length of time. When the fly

5 wheel and shaft cease to rotate the toy cannot fall off of the track because of the guard 12. The guard 12 permits of the device being inserted on the track by forcing the said track between the jaws 14 of the guard and 10 the said guard permits of the toy assuming different lateral angles on the track without stopping the travel of the toy on such track by virtue of either of the side arms 13 contacting with the track.

15 My improvement is of an extremely simple nature but will afford amusement to both young and old, and while it is thought that the foregoing description, when read in connection with the accompanying drawing 20 will fully set forth my improved toy, it is to be understood that I do not wish to be restricted to details of construction and, therefore, hold myself entitled to make such 25 changes therefrom as fairly fall within the scope of what I claim.

Having described the invention, I claim:

A gyroscopic toy designed for travel on a track whose ends are held and are susceptible to alternate vertical movement to tilt and incline the track, said toy including a wheeled carriage, the wheels of which being arranged for travel on the track and a gyroscope which includes a ring frame journaled on the center 30 of the carriage, a shaft carrying a pull cord freely journaled between the bottom and top of the ring frame, and a fly wheel centrally fixed on said shaft and a guard comprising a member which is fixed adjacent one end of 35 the frame and having depending outwardly inclined arms which merge into inwardly rounded portions that afford jaws and which jaws are in spring contact with each other and said guard receiving the track there- 40 through.

45 In testimony whereof I affix my signature
CHARLES A. McPHERSON.
